CLAIM

The ornamental design for a garment for an animal, as shown and described.

DESCRIPTION

FIG. 1 is a front, right perspective view of a garment for an animal shown in an environment of use showing the new design;

FIG. 2 is a left side view thereof;

FIG. 3 is a right side view thereof;

FIG. 4 is a top plan view thereof; and,

FIG. 5 is a front elevational view thereof.

The dash-dot-dot lines showing an animal depicted in FIGS. 1-5 illustrate environmental subject matter only and form no part of the claimed design.

1 Claim, 5 Drawing Sheets
